UNITED STATES PATENT OFFICE.

JAMES J. DUFFY AND FRANK A. KELL, OF CHICAGO, ILLINOIS.

RAIL SUPPORT AND TIE PROTECTOR.

Application filed April 30, 1923. Serial No. 635,679.

To all whom it may concern:

Be it known that we, JAMES J. DUFFY and FRANK A. KELL, citizens of the United States, residing at Chicago, in the county 5 of Cook and State of Illinois, have invented certain new and useful Improvements in Rail Supports and Tie Protectors, of which the following is a specification.

The present invention relates to tracks 10 and more particularly to such made of cross ties embedded in suitable ballast or otherwise supported and on which are surmounted the rails. While the invention is particularly well adapted for use where the 15 ties are of wood, it may be applied with certain advantages to ties of other material, such as cement.

The principal objects of the invention are, 20 to provide devices for supporting the rails of tracks to a greater extent than the mere contact of the base of the rail with the tie, and without the interposition of so called tie plates between the base of the rail and the tie; to provide for such support with a 25 minimum of material used in the manufacture of such supporting devices; to protect the ties by spreading the load coming thereupon to a greater extent than results from the ordinary base contact of the rail with 30 the tie; and to prevent alteration of the track gage incident to rolling stock passing over the track which has a tendency to cause the ties to become slewed.

Another object of the invention is to provide 35 a rail support which will more effectively resist lateral tipping of the rail by forming the support with a wider tie engaging portion, to be disposed at one side of the rail (that side toward which the rail 40 is most likely to tip), than the tie engaging portion at the opposite side of the rail.

Other objects and advantages of the invention will appear in the following detailed description, taken in connection with 45 the accompanying drawings, forming a part of this specification, and in which drawings:

Figure 1 is a plan view of fragments of 50 companion rails of a track, mounted upon a tie with rail supports and tie protectors applied thereto.

Fig. 2 is an enlarged sectional view on the line 2—2 of Figure 1, the tie being shown in elevation.

Fig. 3 is an enlarged sectional view on the 55 line 3—3 of Figure 1, the rail being shown in elevation.

Fig. 4 is a perspective view of the rail support and tie protector.

In the drawings, where similar characters 60 designate like parts throughout the views, A is a cross tie, B rails resting thereupon, C the preferred embodiment of the present invention,—the rail support and tie protector, and D suitable devices, such as spikes, 65 for securing the rail to the tie and maintaining the rail support and tie protector C in place.

The ties of the track may be of wood or other suitable material preferably provided 70 with a substantially flat upper face 5 and of substantially uniform width so that the sides 6 may both be engaged by portions of the rail support.

The rail may be of any preferred or 75 standard cross section including a base 7 adapted to rest upon the face 5 of the tie.

Referring now to rail support C it is preferably formed of cast metal in a unit and includes relatively wide flat elongated plate 80 portions 8 and 9 to engage the upper face 85 of the tie A at opposite sides of the base 7 of the rail B, and extending longitudinally of the base, the lower major face 10 of each plate portion to contact with the tie; and relatively wide flat elongated plate portions 11 to engage the under face of the base 7 90 of the rail B at opposite sides of the tie A, and extending longitudinally thereof with the upper major face 12 of each portion 11 to contact with the base 7 of the rail B.

The plate portions 8 and 9 are in spaced apart relation, a distance substantially the width of the base of the rail, so that the minor faces 13 of these portions 8 and 9, which are adjacent one another, contact 95 with the base of the rail as clearly shown in Figure 2 of the drawings. The plate portions 11 are also in spaced apart relation substantially the width of the tie A, so that the minor faces 14 of these portions 11 contact 100 with the sides 6 of tie A.

The plate portions 8, 9 and 11 are joined together so as to provide a rectangular opening 15, as shown in Figure 4 of the drawings, bounded by the minor faces 13 and 14 of the plate portions 8, 9 and 11, and this opening permits the base of the rail to contact with the upper face 5 of the tie A, without the interposition of metal between the base 7 of the rail and the tie. The 110 juncture between plate portions 8 and 11 is indicated at 16, where the metal is rela-

tively thicker than the metal at each side of the juncture, and the juncture between the portions 9 and 11 is indicated at 17, also relatively thicker.

- 5 The plate portion 8 is made relatively wider than the plate portion 9 and in practice it is preferred to dispose the relatively wider plate portion at that side of the rail B where it will most effectively resist the lateral tipping of the rail. For instance in Figure 1, which may indicate, by way of example, a comparatively straight run of track, the relatively wider plate portions 8 are disposed outermost, and hence if there 10 is a tendency for the rail to tip, such will be counteracted by the relatively wide plate portions 8 engaging the upper face of the tie, and to which the forces are transmitted, coming upon the rail, through the devices 15 D and the engagement of the base of the rail, with the plate portions 11.

It is preferred to provide the plate portions 8 and 9 with ribs 18 extending longitudinally thereof and projecting upwardly 20 from the plate portions, as clearly shown in Figure 4 of the drawings, these ribs 18 continued beyond the junctures 16 and 17 and connected to the end portions of the plate portions 11, as at 19. These ribs reinforce 25 the plate portions 8 and 9, preventing them from arching and also have a tendency to reinforce the plate portions 11, which are preferably provided with ribs 20 extending longitudinally of and projecting downwardly from the plate portions 11.

For the accommodation of the shanks of spikes D, the plate portions 8 and 9 are recessed inwardly from the minor faces 13, as shown at 21, these recesses of a size to 30 receive, without play, the shanks of the spikes, so that the heads of the spikes may engage the plate portions 8 and 9, as well as the base 7 of the rail, as shown in Figure 2 of the drawing.

It will be observed that, by use of the rail support and tie protector the tie is maintained in a position with its longitudinal axis at a right angle to the axis of the rail where the track is substantially straight, or radially of curved rails and hence there is no tendency for the gage of the track to be destroyed as results where a tie may creep with one rail. The life of the rail is prolonged, due to the fact that it is supported, not only by its usual engagement with the tie, but also due to the arrangement of the plate portions 11, with their major faces engaging the under side of the rail, giving, in the example shown, substantially 100% additional support for 60 the rail. This is accomplished with a minimum amount of material going into the rail support, for there is no metal interposed between the bottom of the rail and the tie.

Changes in details may be made without departing from the spirit or scope of the invention; but,

We claim:

A rail support and tie protector formed as an integral structure and having side portions and end portions formed of flat plates, the end plates being adapted to engage sides of a tie and the side plates being adapted to extend in crossed relation to a tie with their end portions extending over the inner side 75 portions of the end plates and rigid therewith, ribs extending longitudinally of the side plates upon their upper faces and intermediate the width thereof and having their end portions extending beyond the 80 ends of the side plates and across the end portions of the end plates and inclined towards each other, and depending ribs extending longitudinally upon the under faces of the end plates and intermediate the width 85 thereof.

JAMES J. DUFFY.
FRANK A. KELL.
